UNITED STATES PATENT OFFICE.

HOWARD A. CHAFFIN AND FRANK C. HOLMES, OF CHICAGO, ILLINOIS, ASSIGNORS TO ENOZ CHEMICAL COMPANY, OF CHICAGO, ILLINOIS, A CORPORATION OF ILLINOIS.

SPRAYER.

Application filed November 8, 1922. Serial No. 599,635.

This invention relates to improvements in sprayers.

An object of our invention is to provide a simple and efficient portable liquid sprayer, 5 having means for detachably connecting the same to commercial liquid storage containers of various sizes and capacities, and wherein the parts of the sprayer are so arranged and proportioned that the intake of the same 10 will always extend to the proper depth into containers of different depths to assure the complete removal of the entire contents thereof.

A more specific object of the invention is 15 to provide a device of the character indicated comprising a pump barrel, a piston working in the pump barrel and a hollow piston rod having one end connected to the piston and the other end terminating in a 20 spraying nozzle, together with means comprising a stopper acting member of varying diameter in cross-section surrounding said barrel and adapted to be inserted in the different sized necks of containers of varying 25 sizes for holding the pump barrel in proper position within the container.

In the drawings forming a part of this specification, Figure 1 is a longitudinal vertical sectional view of a sprayer embodying 30 our improvements, showing the same in position within a container also in section, and Figure 2 is a longitudinal sectional view 35 through the spraying nozzle.

In said drawings, 10 indicates a sheet 35 metal container of well known construction provided with a screw threaded neck 111 adapted to receive the usual screw threaded closure cap.

The sprayer comprises a barrel 112 having 40 secured therein at its lower end a reducing member 13 by soldering the same thereto or attaching the same in any other well known manner.

A hollow reciprocating piston rod 16 is 45 slidably mounted within the barrel 112 and has connected thereto at its lower end by soldering the same thereto or securing the same in any other well known manner, a connecting fitting 17 having a reduced screw threaded lower end 18 adapted to receive the piston member 19. The piston member 19 consists of a pair of cup-shaped washers 20 and 21 held in place against the shoulder 22 by a nut 23 screwed on to the threaded

end of the fitting 17. The fitting 17 is provided with a central bore 24 to provide communication between the inner portion of the hollow piston rod 16 and the interior of the barrel 12. A valve seat 25 is formed at the upper end of the bore of the fitting 17 and a ball check valve 26 is adapted to co-operate therewith.

The barrel 12 is also provided with a check valve comprising a ball 27 adapted to co-act with the seat 28 formed at the upper 65 end of the tube 114.

A stopper member 129 is shown of tapering or frusto-conical form and is adjustably connected with the barrel 112 of the sprayer. As shown, the barrel 112 has its upper end 70 provided with exterior steep pitch screw threads 150 and has secured to the upper end thereof a cap 135 having a downwardly projecting annular flange 136 engaging with the uppermost thread of the threads 150 and 75 having a guide opening 151 therein receiving the upper end of the piston rod 116.

The stopper member 129 comprises an inner threaded nut member 152 engaging with the threads 150 on the barrel 112, and an outer conical sleeve member 153 secured to the nut 152 by solder or any other well known means. Secured to the upper end of the nut 152 and sleeve 153 is a disc 154 having laterally projecting wings 155 adapted to 85 serve as finger rests.

The upper end portion 39 of the hollow piston extends at right angles to the major portion thereof and is connected thereto by the curved portion 48. The outer end of the tubular portion 39 is provided with a spraying nozzle or tip 40. The tip 40 as clearly shown on Figure 2 is provided with interior screw threads 41 in threaded connection with a fitting 42 receiving the end of the tube 39 and being secured thereto by solder or any other well known means. A plug 43 is received within the cap 40, the former being provided with threads engaging with the threads 41 of the cap 40. The plug 43 is provided with oppositely located diagonal grooves 44 forming ports to convey the liquid from the tube 39 to the front end of the cap to thereby produce a whirling action of the fluid as it passes through the tip. The plug 43 is also provided with a rearwardly projecting cylindrical post 45 loosely received within the end of the tube 39 to there-

by provide an annular recess 46 to direct the liquid to the inner ends of the ports 44. The outer end of the cap 40 is provided with a small perforation 47 through which the liquid is sprayed.

In operation the device is adapted to be inserted in the vessel 110, the conical stopper 129 being fitted within the mouth 132 of the neck 111 of said receptacle. Should the lower end of the tube 114 not extend to the proper depth into the vessel to assure the removal of the entire contents, the barrel 112 may be rotated within the nut 152 thus adjusting the sleeve downwardly toward the bottom 15 of the vessel. It will be evident that due to the conical construction of the stopper 129, the same is adapted to fit the various sizes of mouths of different capacity containers, and that due to the screw threaded adjustment provided between the stopper 129 and the barrel 112, the barrel 112 together with the tube 114, may be adjusted to correspond to the varying depth of vessels of different capacity and size. The finger rests 155 are 25 then engaged by the operator and the piston 16 is reciprocated. Upon upward movement of the piston rod 16, liquid will be drawn upwardly through the tube 114 into the barrel 112 of the sprayer. During this upward movement of the piston it is obvious that the valve 26 will be closed while the valve 28 will be open to admit the fluid. Upon the next 30 downward stroke of the piston rod 16, the valve 28 will be closed and the valve 26 will be forced open due to the upward pressure of the liquid, and the liquid forced through the hollow piston rod 16. During successive reciprocations of the piston rod 16, the liquid will be forced through the hollow piston rod 35 past the plug 43, a whirling motion being imparted to the same by passage through the ports 44, and will finally be sprayed through the small opening 47 in the cap 40.

We have herein shown and described what 45 we now consider the preferred manner of carrying out the invention, but the same by way of description only, and not by way of limitation. All changes and modifications are contemplated that come within the 50 scope of the claims appended hereto.

We claim:

1. In a sprayer adapted to be detachably associated with containers of different depth and having delivery openings of different diameters, said sprayer including: a pump barrel of a greater length than the depth of the deepest container with which the sprayer is adapted to be associated, said pump barrel having an intake orifice at its inner end arranged to be positioned at the bottom 55 of any one of the containers; a piston within said pump barrel; a hollow piston rod connected to said piston and extending outwardly beyond the outer end of the pump barrel and terminating with a spray nozzle, and the said piston rod being formed outwardly of the pump barrel, to provide a hand grasp for reciprocation; intake and outlet valves associated with said pump barrel and piston; a plug adjustably threaded on the exterior of said pump barrel, said plug being exteriorly formed to adapt it for co-operation with the discharge openings of varying diameters of the containers; and finger pieces located adjacent said plug and 60 extending laterally of the sprayer whereby the sprayer may be held in proper position in the container by said finger pieces by one hand of the operator and the piston and piston rod operated by the other hand of the 65 operator.

2. In a spraying device, the combination with a pump barrel adapted to be inserted into containers having various sized orifices, and of various capacities; of means for supporting said barrel in a container, said supporting means having a graduated contour whereby orifices of different sizes may be snugly engaged; and means connecting said barrel and supporting means whereby rotation of said barrel relative to said supporting means effects longitudinal movement of said barrel with respect to said container for adjusting the barrel in containers of varying capacity while in operative position.

In witness that we claim the foregoing we have hereunto subscribed our names, this 31st day of October A. D. 1922.

HOWARD A. CHAFFIN.
FRANK C. HOLMES.
